B. VOM EIGEN.
BAG FRAME FASTENER.
APPLICATION FILED DEC. 24, 1914.

1,153,654.

Patented Sept. 14, 1915.

UNITED STATES PATENT OFFICE.

BENNO VOM EIGEN, OF NEWARK, NEW JERSEY, ASSIGNOR TO AUGUST GOERTZ & CO., A CORPORATION OF NEW JERSEY.

BAG-FRAME FASTENER.

1,153,654.

Specification of Letters Patent.

Patented Sept. 14, 1915.

Application filed December 24, 1914. Serial No. 878,862.

To all whom it may concern:

Be it known that I, BENNO VOM EIGEN, a citizen of the United States, residing at Newark, in the county of Essex and State 5 of New Jersey, have invented certain new and useful Improvements in Bag-Frame Fasteners; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15

This invention relates, generally, to improvements in bag-frame fasteners; and, the present invention has reference, more particularly, to a novel spring-controlled fastener or catch for the hinged sections of bag-frames of the various kinds.

The present invention has for its principal object to provide a neat and simply constructed bag-frame fastener or catch of the 25 general character hereinafter more fully set forth, the parts of which have been reduced to a minimum and cannot readily get out of order, are easily assembled in their operative relation, and are readily manipulated.

The invention has for its further purpose to provide a pivotally disposed knob or fingerpiece, in the form of a bag-frame catch, which is adapted to be secured directly upon 35 the upper portion of one of the frame-sections, the knob or fingerpiece being in the form of a hollow element into which extends a fixed post and is provided with a spring co-acting with said post and with a portion 40 of the interior wall of the knob, to permit of a rearwardly pivotal movement of the said knob, and also to return the knob or fingerpiece to its normal initial position after manipulation.

Other objects of the present invention not at this time more particularly enumerated will be clearly understood from the following detailed description of the invention.

With the various objects of the present 50 invention in view, the said invention consists, primarily, in the novel bag-frame catch or fingerpiece hereinafter set forth; and, the invention consists, furthermore, in the novel arrangements and combinations of the various devices and parts, as well as in the de-

tails of the construction of the said parts, all of which will be more fully described in the following specification and then finally embodied in the clauses of the claims which are appended to and which form an essential part of the said specification. 60

The invention is fully illustrated in the accompanying drawings, in which:—

Figure 1 is a front elevation of the frame-sections of a bag-frame in their closed relation, with a bag-frame catch or fastener representing one embodiment of the principles of the present invention, the same being also shown in front elevation; and Fig. 2 is a vertical sectional representation of the 70 hinged bag-frame-sections represented in an open relation, with the bag-frame catch or fastener shown in side elevation, in its pivotally mounted position upon one of said frame-sections. Fig. 3 is a detail vertical 75 section, on an enlarged scale, said section being taken on line 3—3 in said Fig. 1; and Fig. 4 is a horizontal section, taken on line 4—4 in said Fig. 4, with the post and spring disposed within the hollow knob or finger-piece represented in top view. Fig. 5 is a transverse vertical section of a cylindrical box-like element employed with the hollow knob or finger-piece, shown detached from said knob or fingerpiece; and Fig. 6 is a 80 view of the same looking in the direction of the arrow α in said Fig. 5. Fig. 7 is a front 85 view, Fig. 8 a rear view, and Fig. 9 a side elevation of the post employed with the bag-frame catch or fastener, but shown detached 90 from the frame-section.

Similar characters of reference are employed in all of the above described views, to indicate corresponding parts.

Referring now to the said drawings, the 95 reference-characters 1 and 2 indicate the usual bag-frame sections which are hinged in any suitable manner, as at 3. Suitably mounted upon the upper central portion of one of said frame-sections, as 1, is a post 4, 100 said post being provided with downwardly extending rivet-lugs 5 which project through suitably disposed holes or perforations in said portion of the frame-section 1 and are upset or riveted upon the lower surface-portion 105 of said frame-section, substantially as shown in Fig. 3 of the drawings. At its upper end-portion the said post 4 has a finger 6 projecting in a forward direction from the front face of the post, the said 110

front face of the post being also formed near the lower portion of the post with a projection, as 7, having an inclined or tapering surface, as 8. Forced out of the main body of said post, so as to project from the back or rear face of the post, or otherwise connected therewith, is another projection, as 9, the purpose of which will be presently more fully specified. Mounted above the 10 said frame-section 1 and upon the lower portion of said post 4, above the projection 7 and beneath the projection 9 is a cylindrical box-like element comprising a base 10, an annular bead-like flange 11 and an upwardly 15 extending wall 12. The said base 10 is made with a laterally extending opening, as 13, and a longitudinally extending opening, as 14, said openings 13 and 14 communicating with each other, and bounded by corner- 20 portions, as 15. The purpose of these corner-portions 15 is to rest directly upon the projection 7 of the post 4, as shown in said Fig. 3 of the drawings, when the latter is arranged in the open part 13 of said 25 box-like element, and held and secured in its operative position above the upper face of the frame-section 1, by the arrangement of a coiled spring in the manner and for the purposes to be hereinafter more fully stated. 30 The assembled arrangement of said box-like element with relation to the frame-section 1 and the post 4 is that shown in said Fig. 3, and is such, that one-half of said box-like member will extend beyond the edge-portion 35 16 of the frame-section 1, and will lap over upon the other frame-section 2, when the latter is closed against the frame-section 1, so as to enable the bringing of a lock-stud or projection, as 17, upon the 40 frame-section 2 into locked or retaining engagement with the bounding edge-portion 18 of the base 10 of said box-like element, as will be clearly evident from an inspection of said Fig. 3 of the drawings. Mounted 45 upon the previously-mentioned finger 6 of the post 4 is one end of the above-mentioned coiled spring 19, said spring having its other end bearing upon a portion of the inner surface of the wall 12, opposite said 50 finger 6, whereby the parts will be retained in their normal initial positions, indicated in said Fig. 3, as will be clearly evident. Suitably mounted upon said wall 12, with its lower marginal edge resting upon the annular bead 11, by being pressed over said wall and held by friction, or otherwise suitably 55 secured in its position, is a hollow knob, as 20, which forms the fingerpiece of the bag-frame fastener or catch, as will be clearly 60 evident. Normally, the spring 19 retains the complete bag-frame catch or fastener thus provided, with relation to the frame-sections 1 and 2 in the position indicated in Fig. 3 of the drawings, with the lock-stud 17 in its 65 retained engagement with the edge-portion

18 of the base 10, as above stated, when the frame-section 2 is closed against the frame-section 1, the lock-stud 17 having a tapering portion which, as will be understood from an inspection of the drawings, allows the 70 base 10 to ride over said tapering surface and the spring causing said base to spring into locked engagement with said lock-stud. To disengage the said base 10 from its holding engagement with the lock-stud, so as to 75 permit the hinged frame-sections 1 and 2 to be brought into their separated or open relation, a slight pressure upon the portion 21 of the knob 20, will bring the latter into its tilted position, indicated in Fig. 2 of the 80 drawings, so that the two frame-sections can be easily opened, as will be clearly evident. The purpose of the previously-mentioned projection 9 extending from the rear face of the fixed post 4 is to permit of the 85 pivotal movement of the knob or finger-piece and the cylindrical box-like element connected therewith, the lower off-set 22 of said projection with which the bounding edge 23 of the base 10 is brought into contact limiting the pivotal movement of the catch or fastener, as will be evident, and preventing displacement of the catch with 90 relation to the frame-section 1. The upwardly projecting corner-portions 15 have 95 sufficient spring-like action or resiliency, to allow for the above-mentioned pivotal movement of the base 10 and incidentally of the entire box-like element. After the knob 20 has been tilted, and upon the removal of 100 further pressure from the portion 21 of said knob, the compressed and slightly distorted spring 19, in assuming its normal position, will return the raised-knob or fingerpiece, and the parts connected therewith, again assume their normal initial positions indicated in said Fig. 3, as will be clearly evident.

Of course I am aware that some changes may be made in the general arrangements and combinations of the several devices and parts, as well as in the details of the construction of the latter, without departing from the scope of the present invention as set forth in the foregoing specification, and as defined in the clauses of the claims which are appended to the said specification. Hence, I do not limit my present invention to the exact arrangements and combinations of the various devices and parts, as described in the said specification, nor do I confine myself to the exact details of the construction of the said parts, as illustrated in the accompanying drawings.

I claim:—

1. A bag-frame fastener comprising a hollow knob, a post adapted to be secured upon a frame-section, said hollow knob being capable of a pivotal movement independent of and separate from said post, a spring within said knob and in engagement with said post,

and means connected with said post and said knob to permit of and limit the pivotal movement of said knob, substantially as and for the purposes set forth.

5 2. A bag-frame fastener comprising a hollow knob, a post adapted to be secured upon a frame-section said hollow knob being capable of a pivotal movement independent of and separate from said post, a spring with-
10 in said knob and in engagement with said post, a rearwardly extending projection upon said post, and means connected with said knob extending beneath said projection to permit of and limit the pivotal movement of said knob, substantially as and for the purposes set forth.

3. A bag-frame fastener comprising a hollow knob, a post adapted to be secured upon a frame-section, said hollow knob being capable of a pivotal movement independent of and separate from said post, a finger ex-
20 tending forwardly from said post, a coiled spring within said knob having one end ar-
ranged over said finger and its other end in
25 engagement with the wall of said knob, and means connected with said post and said knob to permit of and limit the pivotal movement of said knob, substantially as and for the purposes set forth.

30 4. A bag-frame fastener comprising a hollow knob, a post adapted to be secured upon a frame-section, said hollow knob being capable of a pivotal movement independent of and separate from said post, a finger ex-
35 tending forwardly from said post, a coiled spring within said knob having one end ar-
ranged over said finger and its other end in engagement with the wall of said knob, a rearwardly extending projection upon said
40 post, and means connected with said knob extending beneath said projection to permit of and limit the pivotal movement of said knob, substantially as and for the purposes set forth.

45 5. A bag-frame fastener comprising a hollow knob, a post adapted to be secured upon a frame-section, a cylindrical box-like element connected with said knob, said element comprising a base having an opening and
50 bounding corner-portions, said post being provided with a forwardly extending projection upon which said corner-portions rest and are in engagement, a spring within said knob and in engagement with said post,
55 and means connected with said post and said knob to permit of and limit the pivotal movement of said knob, substantially as and for the purposes set forth.

6. A bag-frame fastener comprising a hol-

low knob, a post adapted to be secured upon a frame-section, a cylindrical box-like ele-
60 ment connected with said knob, said element comprising a base having an opening and bounding corner-portions, said post being provided with a forwardly extending pro-
jection upon which said corner-portions rest and are in engagement, a spring within said knob and in engagement with said post, a rearwardly extending projection upon said post, and means connected with said knob
65 extending beneath said projection to permit of and limit the pivotal movement of said knob, substantially as and for the purposes set forth.

7. A bag-frame fastener comprising a hol-
low knob, a post adapted to be secured upon a frame-section, a cylindrical box-like ele-
70 ment connected with said knob, said element comprising a base having an opening and bounding corner-portions, said post being provided with a forwardly extending pro-
jection upon which said corner-portions rest and are in engagement, a finger extend-
75 ing forwardly from said post, a coiled spring within said knob having one end ar-
ranged over said finger and its other end in engagement with the wall of said knob, and means connected with said post and said knob to permit of and limit the pivotal movement of said knob, substantially as and
80 for the purposes set forth.

8. A bag-frame fastener comprising a hol-
low knob, a post adapted to be secured upon a frame-section, a cylindrical box-like ele-
85 ment connected with said knob, said element comprising a base having an opening and bounding corner-portions, said post being provided with a forwardly extending pro-
jection upon which said corner-portions rest and are in engagement, a finger extend-
90 ing forwardly from said post, a coiled spring within said knob having one end ar-
ranged over said finger and its other end in engagement with the wall of said knob, a rearwardly extending projection upon said post,
95 and means connected with said knob ex-
tending beneath said projection to permit of and limit the pivotal movement of said knob, substantially as and for the purposes set forth.

100 In testimony, that I claim the invention set forth above I have hereunto set my hand this 17th day of December, 1914.

110 BENNO VON EIGEN.
